(57) **CLAIM**

The ornamental design for a shoe with eyelet slit arrangement, as shown and described.

DESCRIPTION

FIG. 1 is a front perspective view of a shoe with eyelet slit arrangement showing my new design;

FIG. 2 is a side view thereof;

FIG. 3 is an opposite side view thereof; and,

FIG. 4 is a second front perspective view thereof.

The sixteen unshaded regions that are demarcated by solid lines (i.e., the regions inside the eyelet slits) form no part of the claimed design. The broken lines depicting the remainder of the shoe show features that form no part of the claimed design.
